UNITED STATES PATENT OFFICE.

ALFRED McEWEN, OF TARRYTOWN, NEW YORK.

UNIVERSAL LEVER COUPLING.

Application filed July 13, 1923. Serial No. 651,261.

To all whom it may concern:

Be it known that I, ALFRED McEWEN, a citizen of the United States, and resident of Tarrytown, in the county of Westchester 5 and State of New York, have invented certain new and useful Improvements in Universal Lever Couplings, of which the following is a specification.

This invention relates to a universal coupling especially, though not exclusively, designed for use in connection with the primary and secondary reducing levers of engraving machines of the kind termed "Microphotographs," that is to say, machines 15 whereby the motions of ordinary writing are transmitted to an engraving point and the written matter, in miniature, thereby engraved in a suitable record surface.

The object of my invention is to provide 20 for primary and secondary levers a coupling having a universal joint that can be adjusted in relation to the fulcrum of the primary lever in a manner to secure a greater or less movement of the secondary lever by actuation 25 of the primary lever, the directional movement of the outer arm of the secondary lever corresponding with, or being reversely of that of the outer arm of the primary lever, as desired.

According to my invention the coupling, 30 in its preferred form, comprises a universal joint composed of an annular supporting member and two oscillating members mounted thereon with their respective axes 35 at right angles to each other; rods fixed centrally to the oscillating members so as to extend upwardly and downwardly therefrom respectively, and provision whereby said rods are slidably and adjustably secured to 40 the reducing levers respectively, to constitute, in effect, parts thereof with a universal joint therebetween, as will be hereinafter described and claimed:

In the drawings—

Fig. 1 is an elevation of an engraving machine equipped with reducing levers embodying my invention.

Fig. 2 is a transverse vertical section of the universal joint and its lever connections.

Fig. 3 is a transverse horizontal section, as on the line 3—3 of Fig. 2.

The typical engraving machine herein illustrated comprises a base 5; standards 6 rising therefrom and supporting a platform 7; and standards 8 rising from the platform and supporting a second platform 9. On

the platforms are mounted two co-operating systems of levers, viz., a vertical system operative to effect the reduction of the motions producing the original writing and to transmit them to the engraving point 10, and a horizontal system that supports the record surface 11 and is operative to control its position in relation to such point.

The reducing system to which my invention is applied embodies two levers 12, 13 suspended in endwise relation to each other from substantial gimbal bearings 14, 15 on the respective platforms, which bearings constitute fulcra that permit the requisite lateral motions of the levers.

In the present instance the shorter arm of the upper lever comprises an L-shaped member 16 extending through the side of its gimbal bearing 14 and carrying the mounting 17 for the engraving point 10. The longer arm of the lower lever depends in proximity to the base 5 and is equipped with a suitable pencil holder 18, including a parallel motion connection that permits the pencil to be freely manipulated by the user and to be brought in writing contact with and throughout the area of a sheet of paper or the like that is suitably clamped to the base.

The upper or shorter arm of the lower lever is connected to the depending longer arm of the upper lever by my improved coupler, which, as illustrated, comprises a ring 19; crossed bars 20 thereon provided with depending end portions 21 that are pivoted to the periphery of the ring by cone-pointed screws, 22, and two vertical rods 23, 24 normally in true axial alignment with the ring; one rod 23 rising from the upper cross bar and the other rod 24 depending from the lower bar. These rods are telescopically fitted in axial bores in the upper and lower levers respectively, so that the universal joint constituted by the ring and cross bars can be raised or lowered as desired in respect to the axis of oscillation of the lever 13, in order to vary the relative lengths of the associated lever arms; a set screw 25 being provided to secure the upper 100 rod in its predetermined positions of vertical adjustment. By adjusting the rod 23 vertically and securing it in place, the universal joint can be nicely adjusted to effect a greater or less movement of the upper lever, 105 when the pencil carried by the lower lever is manipulated, and thus to transmit a pro-

portionate movement to the engraving point, with, perforce, corresponding increase or reduction in the size of the finished product. In other words, the universal coupler can be nicely adjusted in relation to the fulcrum of the lower lever to produce the smallest possible results in the finished engraving, or it can be reversely adjusted to effect a corresponding increase in the size of the work.

From the foregoing it will be seen that the axes 22 of the universal joint can be adjusted in such close relation to the gimbal bearing 15, that no appreciable motion will be transmitted to the engraving point, and that by predetermined upward adjustments of the joint gradient increases in the movement of the point will be effected, such movement corresponding in direction with that of the original writing. It will also be seen that if the universal joint be lowered to position its axes below the axes of the gimbal bearing 15, the motion transmitted to the engraving point will be reversely of the original writing and consequently the minute reduction thus produced may be used for printing purposes.

While I have herein shown and described my novel coupler as applied to the reducing levers of a type of engraving machine it is to be understood that the device may be associated with the compound levers of various other mechanisms.

I claim—

1. The combination with primary and secondary levers having spaced apart fulcra, of a universal coupling for said levers, said coupling comprising a universal joint element having two independently movable members, and adjustable connections between said members and the respective levers, whereby the joint element can be positioned with its axes above or below the fulcrum of the primary lever.

2. The combination with primary and secondary levers having spaced apart fulcra, of a universal coupling for said levers, said coupling comprising a universal joint element having two independently movable members, oppositely-extending rods fixed centrally to the respective members and having sliding connection with the adjacent levers, and means for securing one of said rods in a predetermined position of longitudinal adjustment in respect to its associated lever.

3. The combination with primary and secondary levers having spaced apart fulcra, of a universal coupling for said levers, said coupling comprising a supporting member, two oscillatory members mounted thereon with their respective axes at right angles to each other, oppositely-extending rods fixed centrally to the respective oscillatory members and adjustable longitudinally of the adjacent levers, and means for securing one of said rods in a predetermined position of longitudinal adjustment in respect to its associated lever.

4. The combination with primary and secondary levers having spaced apart fulcra, of a universal coupling for said levers, said coupling comprising a supporting member, two oscillatory members mounted thereon with their respective axes at right angles to each other, oppositely-extending rods fixed centrally to the respective oscillatory members and telescopically fitted to the adjacent levers, and a set screw for securing one of said rods in a predetermined position of longitudinal adjustment in respect to its associated lever.

Signed at New York, in the county and State of New York, this 11th day of July, A. D. 1923.

ALFRED McEWEN.
